DIVER BACK PACK

William D. Walters, 2940 Andros Ave.,
Costa Mesa, Calif. 92626

Filed June 5, 1972, Ser. No. 260,062

Term of patent 14 years

Int. Cl. D3—02

U.S. Cl. D87—1 R

FIG.1

FIG.2

FIG.3

FIG.4

FIG.5

FIG. 6

FIG. 7

FIG. 1 is a front elevational view of a diver back pack showing my new design;

FIG. 2 is a rear elevational view thereof;

FIG. 3 is a left side elevational view thereof, the opposite side being a mirror image;

FIG. 4 is a bottom plan view thereof;

FIG. 5 is a top plan view thereof;

FIG. 6 is a top perspective view; and

FIG. 7 is a bottom perspective view thereof.

I claim:

The ornamental design for a diver back pack, substantially as shown and described.
